UNITED STATES PATENT OFFICE.

ROBERT W. BROOKS, OF POLLARD, ALABAMA.

STALK-FULLER.

1,108,325.

Specification of Letters Patent. Patented Aug. 25, 1914.

Application filed December 26, 1913. Serial No. 808,752.

To all whom it may concern:

Be it known that I, ROBERT W. BROOKS, a citizen of the United States, and residing at Pollard, in the county of Escambia and State of Alabama, have invented certain new and useful Improvements in Stalk-Pullers, of which the following is a specification.

This invention relates to stalk pullers.

The object of the invention is to provide a machine of this character which will rapidly and effectively pull stalks of any description, and deliver them upon a platform, whence they may be discharged by an operator occupying a seat upon the machine. 10
15 A further object of the invention is to provide novel means for securing the positive opening and closing of the stalk gripping or pulling jaws, whereby to insure not only the removal of the stalk from the ground but 20 its release at the proper time, and in position to be removed.

With the above and other objects in view, as will appear as the nature of the invention is better understood, the same consists in the 25 novel construction and arrangement of parts of a stalk puller as will be hereinafter fully described and claimed.

In the accompanying drawing forming a part of this specification and in which like 30 characters of reference indicate corresponding parts: Figure 1 is a top plan view of a stalk puller constructed in accordance with the present invention. Fig. 2 is a view in vertical longitudinal section. Fig. 3 is a 35 fragmentary detail view displaying the mechanism for closing the gripping jaws. Fig. 4 is a detail view on an enlarged scale of one of the grippers. Fig. 5 is a detached detail view of one of the gripper jaws.

40 The frame of the machine comprises, generally stated, two side sills 1, each of which is provided at one end with a lateral arm 2 to which it is designed to attach the swingle trees, (not shown). The side sills are connected adjacent their rear ends by an axle 3 carrying ground wheels 4 of any preferred construction.

As the particular construction of supporting frame does not enter into the construction 50 of the apparatus, further description is deemed unnecessary. Carried by the upper side of each sill is a cam 5, of metal, each being provided with a cut-away portion 6, the function of which will presently appear. 55 Journaled in suitable bearings upon the sills and extending centrally through the cams is

a shaft 7 carrying a drum comprising two heads 8 and connecting slats or bars 9.

Upon the bars is mounted the stalk gripping mechanism which constitutes the essential feature of the present invention, and as the construction of each set of grippers is the same, a description of one will serve for both. Each gripper comprises two jaws 10 having their opposed edges outwardly 65 flared, and pivotally connected at 11 to one of the bars 9, the two jaws being formed at their crotch with a substantially circular recess 12 in which the stalks pass and are gripped, the angular disposition of the opposed edges of the jaws serving to direct the stalks to the recess. Each jaw is provided with a boss or lug 13 to which is pivoted one end of a sleeve 14 which is held against arcuate movement by a clamp 15 secured to 70 the bar. Slidably-mounted in the sleeve 14 is a rod 16, that portion housed within the sleeve being provided with a pin 17 that projects through the slot 18 in the sleeve, and by this arrangement, the rod will be held 75 from accidental disconnection from the sleeve, while being permitted merely to slide therein. The outer end of the bar carries a roller 19 that is designed to travel against the inner face of the cam 5, against which it 80 is held yieldingly by a coiled spring 20, one end of which is secured to a projection 21 on the arm, the other end being secured at 22 to the bar 9.

Rigidly secured to the under side of each 90 of the sills and in the path of movement of the series of rollers 19, is a cam projection 20', the object of which is to close the jaws after they have gripped the stalk, the plain surfaces of the two cams holding the 95 jaws closed until the rollers reach the cut-away portions 6, whereupon the springs 20 will perform their function, and throw the jaws open, thus permitting the stalk to be deposited upon a platform 22' supported 100 at the rear end of the frame, down which the removed stalks may slide, or may be forked off by an operator occupying a seat 23 on platform 22' near one side of the platform. A means for imparting rotary motion to the drum comprises a gear wheel 24 that is rigidly mounted upon the axle 3 and meshes with a gear 25 rigidly mounted upon the shaft 7.

In operation, as the machine is being 110 drawn in the direction indicated by the arrow in Fig. 1, the rollers of one set of

gripper arms will contact with the cams 20', thereby closing the jaws around the stalk, which has previously entered between them, and into the crotch or notch 12, and 5 as stated, the jaws will be held closed by the rollers traveling against the plain opposed faces of the cams until they reach the cut-away portions 6, whereupon the jaws will be instantly opened, and the stalk is 10 lodged upon the platform from whence it may be removed in any suitable manner.

It will be seen from the foregoing description that although the improvements herein defined are simple in character, that 15 they will be thoroughly efficient for the purposes, designed and will coöperate in the production of an effective and thoroughly practical stalk puller.

What I claim as new is:

- 20 1. In a stalk puller, a supporting frame, a drum carried thereby, gripping jaws pivotally-connected with the drum, a sleeve pivotally-connected with each jaw, a spring drawn bar slidably-mounted in each sleeve 15 and carrying at its outer end a roller, cams

supported by the frame to be engaged by the roller, the opposed faces of the cams being provided with cut-away portions to permit release of the jaws, and cams depending from the under side of the frame 20 and in the path of travel of the rollers to effect their closing.

2. In a stalk puller, a supporting frame, a drum carried thereby, a pair of outwardly converging jaws pivoted to the drum, a sleeve pivotally connected with each jaw, a spring drawn bar having a sliding connection with each sleeve, a roller carried by the outer end of each bar, cams supported by the frame, each provided with a cut-away portion serving to release the jaws, and cams depending from the under side of the frame and arranged in the path of travel of the rollers to close the jaws.

In testimony whereof I affix my signature in presence of two witnesses.

ROBERT W. BROOKS.
